UNITED STATES PATENT OFFICE

EENST F. W. ALEXANDERSON, OF SCHENECTADY, NEW YORK, ASSIGNOR TO GENERAL ELECTRIC COMPANY, A CORPORATION OF NEW YORK

RADIO SIGNALING SYSTEM

Application filed May 9, 1925. Serial No. 29,210.

My present invention relates to antennæ for radio signaling systems.

It is an object of my invention to provide means for producing signals by means of a new type of radiation which I have discovered.

The radiator which, up to the present, has been almost exclusively employed for radio communication is a vertical current carrying conductor or a multiplicity of vertical conductors. The horizontal portions of such antennæ systems are not usually employed to produce radiation. In the T antenna, for example, the horizontal currents are opposing at any one time and any tendency to radiate is therefore neutralized, while in the multiple tuned antenna similar conditions occur. In the L antenna, while it is conceivable that the horizontal portion may produce a radiation, the proportion of antenna height to wave length radiated is such that the radiation from the horizontal portion is either negligible or neglected in determining the radiation effect of the antenna.

With the above described types of antennæ systems radio waves emitted are sent out in a horizontal direction parallel with the earth. These waves are subject to certain laws of attenuation and absorption which are expressed by the well known Austin formula. In accordance with this formula there are two factors which determine the attenuation of a wave. One of these factors is distance, i. e., the attenuation of a wave is directly proportional to the distance travelled by the wave. In other words, the amplitude of the wave would be inversely proportional to the distance travelled by the wave if this type of attenuation were the only one with which we had to deal.

It has recently been established by various observers that a wave may be projected into space at a high angle over the horizon, and that such a wave apparently travels in the upper stratas of the atmosphere suffering less attenuation than would be indicated by the Austin formula. The theory has thus become accepted that there are two forms of wave propagation, one being the earth bound

wave with high attenuation, and the other a space wave with lower attenuation.

The new type of radiation which I have discovered belongs to the class of radiation which may be characterized as high angle or space radiation. I have found, however, that it has different characteristics from the high angle space radiation that has been observed heretofore. This may be explained on the ground that the radiation of either the earth bound type or the high angle type heretofore observed is vertically polarized, whereas the new type which I have discovered is horizontally polarized. By horizontally polarized radiation I mean to indicate radiation in which the electrostatic oscillations are in a horizontal plane and the magnetic oscillations in a vertical plane.

While the vertically polarized high angle radiation which has been observed by others has been known to travel long distances with a low absorption, I have found that a portion of this radiation returns to earth within a short distance of the station and produces a response or interference in ordinary receiving sets. I have found, on the other hand, that horizontal polarized waves produce practically no impression on receiving sets adjacent the transmitting station or within a wide range of the transmitter, while at a still greater distance the signals produced by the horizontally polarized radiation are stronger than the signals produced by the vertically polarized radiation of the same power. When the horizontally polarized radiation is received at a long distance from the transmitting station it has the same characteristics as the ordinary vertically polarized radiation. This may be due to the fact that the wave which started in the horizontal plane of polarization gradually changes its plane of polarization so that after having travelled a great distance it becomes a vertically polarized wave.

A horizontal conductor carrying oscillating currents and mounted at a height over the earth of the magnitude of a quarter wave length of the wave to be radiated produces a horizontally polarized radiation at right angles to the length direction of the radiator.

The radiation produced by this radiator proceeds vertically upwards and at various angles over the horizon, and any radiation that would occur parallel to the earth is short circuited by the earth. The radiation, however, that proceeds at an angle of 45° over the horizon probably produces the greatest effect.

Radiation from a horizontal radiator as above described has been measured at various distances from the transmitting station, and compared with similar measurements of ordinary waves. For horizontally polarized waves these measurements show a field intensity in the neighborhood of the station which is practically zero. At a distance of fifteen kilometers (300 wave lengths) from the station the wave was found to be two thirds as strong as the ordinary or vertically polarized wave whereas at 300 kilometers (6000 wave lengths) from the station the horizontally polarized wave was twice as strong as the ordinary wave.

A horizontal radiator as above described also produces high angle radiation in the direction of its own length. The longitudinal radiation proceeding at a 45° angle over the horizon shows characteristics intermediate the purely horizontally polarized and the purely vertically polarized radiation. Thus it has been found that at a very short distance from the transmitting station the longitudinal radiation from a horizontal radiator is considerably weaker than the radiation from a vertical radiator. As observations are made at increased distances from the station in the direction of the length of the radiation the intensity of the signals received from the horizontal radiator rapidly approaches the intensity of the signals received from a vertical radiator whereas at right angles from the horizontal radiator the signals are still much weaker than the signals from the vertical radiator.

The above discoveries have led me to design an antenna system for communication over long distances which creates practically no signals or interference in the neighborhood of the station. The novel features which I believe to be characteristic of my invention are set forth with particularity in the appended claims. My invention itself, however, both as to its organization and method of operation together with further objects and advantages thereof will best be understood by reference to the following description taken in connection with the accompanying drawing in which Fig. 1 shows diagrammatically an antenna whereby horizontally polarized waves may be produced. Fig. 2 shows diagrammatically a tuned loop radiator adapted to produce horizontally polarized radiation. Fig. 3 shows diagrammatically two horizontal radiating conductors adapted to produce horizontally polarized radiation, in combination with phase shifting devices

for controlling the direction of the radiated beam. Figs. 4 to 12, inclusive, show diagrammatically modifications of the radiators shown in Figs. 1 to 3 inclusive, each modification being adapted to produce horizontally polarized waves.

In the simplest form of my invention, as indicated in Fig. 1, the antenna is composed of a horizontal radiator 1 suspended between insulators 2 which are spaced apart a distance substantially equal to one half wave length of the wave to be radiated. The radiator is mounted at a height above the earth of approximately one quarter of a wave length of the wave to be radiated, and is supplied at its middle point with high frequency oscillating currents by means of a source 3 and a transformer 4. At any given instant the current in radiator 1 is in one direction only. The current in the connecting or transmission lines 5 and 6 however always flows in opposite directions as indicated by the arrows thus providing a non-radiating connection between the source of current 3 and the radiator 1. With a radiator of the type disclosed in Fig. 1, response registered by an ordinary receiver set in the neighborhood of the transmitter is practically negligible, although a strong response is produced at greater distances. A radiator of the simple type shown in this figure, however, is not very directive.

In Fig. 2 I have shown a loop antenna 7 tuned by condensers 8. The condensers are so spaced that the series capacities neutralize the series inductances. Each side of the loop has a length equal to about one quarter of a wave length of the wave to be radiated, although the lengths of the sides may be equal to one half a wave length if desired. The current is introduced through the end of the loop by means of non-radiating transmission lines 9 and 10. The upper portion of the loop is mounted above the earth a distance equal to at least one quarter of a wave length of the wave to be radiated. The lower portion of the loop may therefore be very close to the earth. With this type of radiator it is possible to obtain both horizontal and vertically polarized radiation. With current flowing in the loop, as indicated, vertically polarized radiation takes place endwise of the loop. Perpendicular or broadside to the loop, however, the vertically polarized radiation is neutralized and the only radiation obtained is horizontally polarized radiation.

The condensers 8 associated with the loop are spaced apart approximately one eighth of a wave length but less than one quarter of a wave length of the radiated wave. When condensers are spaced apart a distance greater than one quarter of a wave length of the wave to be radiated the antenna will have more than one degree of freedom, i. e. it may have more than one system of oscillations at that frequency or closely adjacent frequencies.

cies. By employing condensers spaced apart approximately one eighth of a wave length of the wave to be radiated I have found that this difficulty may be overcome and the oscillations confined to one system at that frequency or closely adjacent frequencies.

In the form of my invention shown in Fig. 3 I have indicated an antenna comprising a combination of two radiators 11 and 12 of the type disclosed in Fig. 1, both radiators being fed at the middle point with high frequency current from a source 3 and transformers 13 and 14 and through non-radiating transmission lines 15—16 and 17—18. The radiators are spaced between centers about one half a wave length of the wave to be radiated, and each radiator is approximately one half a wave length in extent. Associated with each pair of transmission lines are phase shifting devices 19 and 20 which control the phase relation in the currents of the two radiators. By varying the phase relation of the currents in radiators 11 and 12 the direction of radiation may be controlled. Thus, if the currents in the two radiators flow simultaneously in the same direction the combined radiation will be a maximum upwards and at right angles to the direction of the radiator. If, on the other hand, the currents in the two radiators are of opposite phase, the radiation will be a maximum in a direction 45° upwards in the length direction of the radiators. The radiators are mounted above the earth a distance equal to, at least, one eighth of a wave length of the wave to be radiated.

In Fig. 4 I have shown two substantially square radiating loops 21 and 22 of the type disclosed in Fig. 2 and tuned by condensers 23. The sides of the loops vary in length from one quarter to one half a wave length of the wave to be radiated. The upper side of the loop should, at least, be one quarter of a wave length above the earth while the lower side may be very close to the earth. If current rotation in both loops is clockwise, and the distance between centers of the loops equals substantially one half a wave length of the wave to be radiated, the resulting radiation from the vertical sides of the loop is neutralized in all directions, and all radiation takes place from the upper horizontal conductors. The directive characteristics of the resulting radiation depends, as in Fig. 3, on the phase relation of the currents in the two loops. Phase shifting devices 24 and 25 control the phase relation of the currents in the two loops and high frequency current 55 is supplied to the radiators through non-radiating transmission lines.

In the form of my invention shown in Fig. 5 I have indicated an antenna comprising two horizontal radiators 26 and 27 of the type disclosed in Fig. 1, the radiators being mounted

opposite and parallel to each other, and fed by non-radiating transmission lines. The distance between the suspending insulators 2 and the distance between the two radiators is approximately one half a wave length of the wave to be radiated. The radiators are mounted above the earth a distance equal to at least one eighth of a wave length of the wave to be radiated. As in Figs. 3 and 4 phase shifting devices 28 and 29 control the phase of the current in the two radiators. In this case if the currents in the two radiators are of opposite phase the maximum radiation is 75 45° upwards, and in a direction at right angles to the length direction of the radiators. Further directional control may be obtained if desired by adjusting the distance between the radiators.

In Fig. 6 I have shown a modification of the radiator shown in Fig. 1. The radiator 30 of this figure is fed by non-radiating transmission lines, and has a length equal to one or more wave lengths. Series condensers 31, which are spaced apart a distance less than one quarter of a wave length, neutralize 80 the series inductances as in the case of the loop radiator and confine the oscillations to one system at the frequency employed or closely adjacent frequencies. The use of a plurality of condensers further serves to artificially prolong the length of the radiator and thus enable a greater directive effect to be obtained. The type of radiator shown in this figure will give a high angle horizontally polarized broadside beam. As in the previous figures the antenna is mounted above the earth a distance equal to at least one eighth of a wave length of the wave to be radiated and is supplied with high frequency current through non-radiating transmission lines.

In Fig. 7 I have indicated a substantially square horizontal loop radiator 32 fed by non-radiating transmission lines. As in the previous figures, series capacity units 33, spaced apart a distance less than one quarter 100 of a wave length, neutralize the series inductances. Each side of the square may vary in length from one quarter to one half the wave length of the wave to be radiated. With this type of radiator, horizontally polarized radiation, directed to all points of the compass, may be obtained. The effect produced may be likened to a spray fountain. The radiator is mounted above the earth, at least, one eighth of a wave length of the wave to be radiated and is supplied through non-radiating transmission lines.

The series tuned radiator 34 shown in Fig. 8 is similar to that shown in Fig. 7. The length of the loop is one wave length or more, and the width approximately one quarter to one half of a wave length of the wave to be radiated. The condensers 35 associated with the loop neutralize the series inductances and are spaced apart less than one quarter of a 115 120 125 130

wave length. As in the previous figures the loop is fed with current through non-radiating transmission lines. This type of radiator gives a horizontally polarized high angle broadside beam.

Fig. 9 shows a radiator 36 similar to that shown in Fig. 6 in combination with a reflector 37. The radiator and reflector each have a length of one wave length or more of the wave to be radiated, and are separated by one quarter to one half a wave length. Condensers 38 are spaced apart less than one quarter of a wave length and radiator 36 is fed through non-radiating transmission lines as in the previous cases.

Fig. 10 shows a further modification of an antenna providing horizontally polarized waves. In this figure the radiators 39 and 40 are substantially identical with the radiator shown in Fig. 6. As in the previous figures condensers 41 are spaced apart less than one quarter of a wave length. The distance between the radiators and the phase of the currents in the two radiators may be adjusted as desired to give the desired angle of elevation of the horizontally polarized radiation. Each radiator has a length equal to at least one wave length of the wave to be radiated and is supplied through non-radiating transmission lines. Phase shifting devices 42 and 43 are associated with the transmission lines.

Fig. 11 shows a further modification employing three radiators 44, 45, and 46 and spaced neutralizing condensers 47. As in Fig. 10 the distance between radiators and the phase of the currents in the radiators may be adjusted to give the desired angle of elevation to the radiated beam. The provision of a plurality of radiators has the effect of narrowing the radiated beam both in the horizontal and vertical direction. Phase adjustment of the currents in the radiators may be made as in the previous cases by phase adjusting means 48, 49 and 50.

Fig. 12 shows a further modification of a loop antenna. The antenna 51 shown in the figure is similar to that shown in Fig. 8 but is adapted to be swung into various positions as indicated by the dotted lines 52 and 53. The direction of the radiated beam may be controlled by varying the position of the antenna. As in Fig. 8 the length of the antenna is one wave length or more. The neutralizing condensers 54 are spaced less than one quarter of a wave length apart and the horizontal portion of the radiator is fed through non-radiating transmission lines as in the other figures. The distance between the horizontal portions of the radiator may be from one quarter to one half a wave length as desired.

In the case of horizontal radiators such as shown in Figs. 1, 3 and 5 to 11, inclusive, the radiators are mounted at a distance above the earth equal to approximately one quarter

of a wave length of the wave to be radiated. The height may vary but should be at least one eighth of a wave length of the wave to be radiated. The radiator in each modification shown on the drawing is fed from a high frequency source through non-radiating transmission lines. While I have shown a current source comprising a high frequency alternator and a transformer, various other arrangements for supplying high frequency currents to the radiators may be employed if desired.

With vertical loop radiators as shown in Figs. 2 and 4, and with the type of loop radiator shown in Fig. 12 the upper horizontal portion of the loop may be one quarter of a wave length above the earth, and the lower portion of the loop may be very close to the earth.

Where a plurality of parallel conductors are employed the distance between the conductors may be varied or adjusted so as to control the direction of the radiated waves or beam. Instead of feeding a plurality of parallel conductors from a plurality of transmission lines the conductors may, if desired, be connected in series as shown in Figs. 9 and 12 and fed from a single pair of transmission lines.

If desired, I may insert condensers or other devices in the transmission lines connecting the high frequency source with the radiators to prevent undesired oscillations which might occur in these lines and generate vertically polarized waves.

Various modifications will readily suggest themselves to persons skilled in the art without departing from the scope of my invention as set forth in the appended claims.

What I claim as new and desire to secure by Letters Patent of the United States, is:—

1. An antenna comprising a radiating loop having its sides in a substantially horizontal plane, said horizontal sides having a length equal to at least a quarter of a wave length of the radiated wave, whereby horizontally polarized waves are produced, and said antenna being mounted above the earth a distance equal to at least one eighth of a wave length of the wave to be radiated, and means for supplying high frequency current to said loop.

2. A series tuned loop antenna arranged in a substantially horizontal plane and at a distance above the earth greater than one-eighth of the wave length of the wave to which said antenna is tuned and said antenna having a horizontal dimension of at least a quarter of a wave length of the wave to which the antenna is tuned.

3. An antenna system comprising a plurality of parallel conductors arranged in a horizontal plane, said conductors being electrically disconnected from the earth, means

for supplying high frequency current to said conductors and means for controlling the phase relation of the current in different conductors thereby to control the direction of the radiated waves.

5 In witness whereof, I have hereunto set my hand this 8th day of May, 1925.

ERNST F. W. ALEXANDERSON.
